CLAIM

The ornamental design for a medical x-ray apparatus as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a first perspective view of a medical x-ray apparatus showing my new design in a first state;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof, showing the medical x-ray apparatus in a second state; and,

FIG. 9 is front view thereof, showing the medical x-ray apparatus in the second state.

The medical x-ray apparatus transitions between the first state and the second state. The period with which one state transitions to the other state forms no part of the claimed design.
